DRAFT EXCLUDER FOR DOORS AND WINDOWS

John Edward Macey, Wombourne, England, assignor to
Cavenco Products Limited, Wolverhampton, England,
a British company

Filed Sept. 7, 1965, Ser. No. 86,883

Term of patent 14 years

(Cl. D13—6)

FIG 1

FIG 2

FIG 3

FIG 4

FIG 5

5

FIG 6 5

FIGURE 1 is a perspective view of a portion of a draft excluder for doors and windows showing my new design;

FIGURE 2 is a rear view of the portion thereof;

FIGURE 3 is a front view;

FIGURE 4 is a plan view;

FIGURE 5 is a section on line 5—5 of FIGURE 6; and FIGURE 6 is an underneath plan view.

The draft excluder is of indefinite length and has throughout its length the shape and configuration typified by the portion of the draft excluder shown in the drawings.

I claim:

The ornamental design for a draft excluder for doors and windows, as shown and described.
